GARMENT OR IRONING PRESS

Ernest Davis, Syracuse, N. Y., assignor to The Prosperity Company, Inc., Syracuse, N. Y., a corporation of New York

Application February 23, 1929, Serial No. 342,221
Renewed November 14, 1931

17 Claims. (Cl. 68—9)

This invention relates to a garment or ironing press, and to actuating mechanism for machines having an opening and closing movement as pressing machines and has for its object, a particularly simple and efficient motor means having inertia means as a fly wheel for storing up the excess energy of the motor when the press is closing and utilizing the stored energy when the head goes under final pressure, particularly for boosting the motor when a toggle is used and approaches a straight line when the press is under heavy final pressure.

The invention consists in the novel features and in the combinations and constructions hereinafter set forth and claimed.

In describing this invention, reference is had to the accompanying drawing in which like characters designate corresponding parts in all the views.

20. Figure 1 is a side elevation of a machine embodying my invention.

Figure 2 is an enlarged sectional view, partly in elevation and partly diagrammatic, of this mechanism and the control therefor.

25. Figure 3 is an elevation partly in section of the lower end of the motor means.

The invention comprises motor means for actuating the movable jaw element or head of a pressing machine, the motor means including a

30. movable inertia means as a fly wheel capable of storing up energy, the inert body being normally disconnected from the motor means, an operator-operated or manually operated member for controlling the actuation of the motor means, 35. the manually operable member having means as a spring for returning it when released to its initial position assumed when the press is open.

It also comprises means controlled by the manual means for connecting and disconnecting the 40. inert body or fly wheel and the motor means, it serving to connect the inertia means or fly wheel to the motor means when the manual means is being operated and held operated, but to disconnect the inertia body or fly wheel from 45. the motor means if the operator releases the manual before the head is closed so that upon the release of the manual control before the head is closed, the press head will not continue its closing movement under the momentum of the 50. fly wheel, but on the other hand, will utilize the momentum to cause the head to go under final pressure as long as the manual means is held in operated position. The inertia body or fly wheel is of particular advantage where its energy contributes toward moving the toggle more nearly

into a straight line and boosts the jaw compression.

I have here illustrated my invention as embodied in a conventional type of pressing machine, the cooperating pressing elements or jaws 60 of which are a buck 1 and a head 2 movable toward and from the buck. The buck is mounted on a suitable bracket 3 which is supported on the table 4 of a frame 5. The buck is usually overlaid with a compressible or spring padding 6 65 of any suitable or well known construction. The head 2 is shown as carried at the front end of a yoke or press lever 7 pivoted at 8 to a standard 9 rising from the frame.

The motor means comprises a motor and motion transmitting connections between the movable member of the motor and the rear arm of 70 the yoke lever 7. The motor here shown comprises a cylinder 10 and a piston 11 movable

therein and the motion transmitting connections 75 between the piston and the rear arm of the yoke lever 7 comprise an angle lever 12 pivoted at its angle at 13 to the base of the frame and at its front end at 14 to the piston or connecting rod 15, the other arm of the lever 16 extending upwardly and being pivoted at 17 to the lower end of the link 18 pivoted at 19 to the rear arm of the yoke lever 7. The arm 16 and link 18 form a toggle.

The piston is single acting and the press is 85 opened up when the pressure in the cylinder is released by counter-springs 20, 21. The inertia member in which the energy is stored is preferably a fly wheel connected to any part actuated by the movable motor member or piston to be 90 actuated thereby. As in the illustrated embodiment of this invention, a motor consisting of a cylinder and piston is used, the fly wheel is most advantageously actuated by the piston rod.

22 designates the inertia fly wheel which is 95 mounted upon a hollow sleeve 23 journalled in a bearing 24 formed in the head 10^a at the lower end of the cylinder 10, the sleeve 23 being free or rotatable in its bearing. The fly wheel is connectible to the piston rod through a clutch 100 device comprising a clutch member 25 fixed to the fly wheel, a clutch head 26 shiftable into and out of engagement with the clutch member 25 and normally out of engagement therewith, this clutch head being rotatable with an axially shiftable shaft 27 journalled in the sleeve 23 and extending crosswise of the connecting rod 15 and having a pinion 28 which meshes with the rack 29 formed on the piston rod 15. The pinion is keyed to the shaft but the shaft is so mounted 110

as to move axially relatively to the pinion. The shaft is shifted in one direction by a spring 30 encircling the shaft and interposed between the pinion 28 and the abutment 31 on the shaft. This 5 spring acts to shift and hold the clutch head 26 to its out position.

The operation of the motor is controlled by operator actuated or manual means, and as the motor here shown is a fluid operated motor the 10 control means consists of valve mechanism, having a valve casing 32 with a normally closed spring pressed intake valve head 33 and a normally open exhaust valve head 34 therein, these valve heads being connected by a stem 35 so that they act as 15 a unit. The valve heads are returned to their normal position by a spring 36.

The intake end of the valve casing 32 is connected to a feed pipe 37 and the casing 32 is connected between the valve heads 33 and 34 to the 20 cylinder by a pipe 38. The valve heads are actuated against the returning spring 36 by a push button 39 acting on a lever 40 which has an arm thrusting against an intermediate lever or rocker 41, the latter thrusting against the stem 42 of 25 the exhaust valve head 34. A returning spring 43 acts on the lever 40 to return it and the push button to their normal position.

Obviously, depression of the push button 39 will close the exhaust valve head 34 and open 30 the intake valve head 33 permitting air or other motive fluid to flow from the feed line 37 through the valve casing 32, pipe 38 through the intake port 44 of the cylinder 10. The valve heads 33 and 34 are held in their manually operated closed- 35 press position after the press head 2 has been moved down close to the buck or after the piston 11 has traveled a predetermined distance on its power stroke by pressure operated means including a diaphragm chamber 45 having a diaphragm 46 therein acting on a sliding stem 47 thrusting against the intermediate lever 41 to hold the valve heads 34 and 33 in their operated positions.

The pressure side of this diaphragm chamber 45 is connected by a pipe 48 to a pipe 49 which communicates with the interior of the cylinder 45 through a port 50^a located in a casing 50, this port being arranged to be uncovered by the piston 11 when the piston has traveled far enough to bring the head 2 down close to the buck 1. The press 50 is opened by exhausting the air from the pressure side of the diaphragm chamber 45 by opening a normally closed spring pressed exhaust valve 51 in a valve casing 52 connected by a pipe 53 to the pipe 48. The exhaust valve 51 is operated 55 by a release lever 54.

In order that two hands may be required to close the press, an additional control valve operated by an additional push button is employed. The reference character 55 designates the additional valve casing having a normally open exhaust valve 56 therein which is operated by a push button 57 through levers 58 and 59. The valve casing 55 is connected by a pipe 60 to the pipe 38, this pipe 60 corresponding to the intake port 44 of the cylinder. The valve 56 is held in its operated or closed position by a diaphragm chamber 61 having a diaphragm 62 therein acting upon a sliding stem 63 which thrusts against the lever 59. The pressure side of the diaphragm 65 chamber is connected by a pipe 64 to the pipe 49, this pipe 64 corresponding to the pipe 48. Obviously, if the push button 57 is not depressed, when the push button 39 is depressed, the air instead of passing into the port 44 from the pipe 38, will waste out through the pipe 60 and ex-

haust valve casing 55. Hence, both push buttons must be depressed to permit the effective flow of air to the cylinder.

When the piston 11 travels far enough to uncover the port 50^a in the casing 50, the air will 80 pass back through the pipe 49, and the pipes 48, 64 to the diaphragm chambers 45, 61 to lock or hold the valves 33, 34 and 56, operated by the push buttons 39, 57, to their manually operated 85 position.

The connecting of the fly wheel 22 with some moving part operated by the motor means 10 is controlled by the valves in the valve casing 32 and incidentally is subject to the operation of the valves operated by the push button 57.

In the illustrated embodiment of my invention, the clutch shaft 27 is shifted by a pressure operated motor as a diaphragm chamber 65 having a diaphragm 66 therein acting on the sliding stem 67 which thrusts against the end of the clutch 95 shaft 27.

The pressure side of the diaphragm chamber is connected by a pipe 68 to the pipe 38 or to the coupling 38^a by means of which the pipe 38 is connected to the port 44 of the cylinder 11. Obviously, when the push buttons 39 and 57 are depressed, the air will pass into the diaphragm chamber 65 to actuate the diaphragm 66 therein and shift the clutch shaft 27 to the left, clutching the fly wheel 22 to the shaft so that the fly wheel 105 is connected to the piston rod 15 through a rack 29 and pinion 28. Thus while the valves 34 and 56 are closed and the intake valve is open, the fly wheel will be actuated and store up energy because it is revolved at high speed thru the gear 110 means 28-29 as the piston rod travels downwardly.

If at any time before the press is closed and the valves locked, the operator removes his hands from either button, the air will be free to exhaust 115 from the diaphragm chamber 65 so that the fly wheel will be declutched and the press head will not be actuated further under the momentum of the fly wheel. When the head comes down on the padding on the buck and the toggle is approaching straightened position, the energy stored in the fly wheel will come into action to boost the power applied to the piston rod 15.

The press opens freely of the inertia fly wheel 22 because the operator has released both two-hand control buttons 39 and 57 at the time he causes the press to open by lifting the release handle 54. Thus the clutch 25, 26 is disengaged as the piston rod returns to starting position. The fly wheel is spun or speeded up only during 130 the power stroke of the motor means 10 and at the end of the power stroke the inertia of the fly wheel is an aid to and augments jaw compression on the work between the head and buck.

What I claim is:

1. In a pressing machine, cooperating pressing elements, one of which is movable toward and from the other, actuating means for the movable element, a manually operated control device for said actuating means, an inertia body and connecting means between the control device and the inertia body for connecting the inertia body to the actuating means.

2. In a pressing machine, cooperating pressing elements, one of which is movable toward and from the other, actuating means for the movable element, a manually operated control device for said actuating means, an inertia body, connecting means between the control device and the inertia body for connecting the latter to the ac- 150

tuating means, and means for holding the control device in operated position.

3. In a pressing machine, cooperating pressing elements, one of which is movable toward and from the other, actuating means for the movable element, a manually operated control device for said actuating means, an inertia body, connecting means between the control device and the inertia body for connecting the latter to the actuating means, and means controlled from the actuating means for holding the control device in operated position.

4. In a pressing machine, cooperating pressing elements, one of which is movable toward and from the other, motor means for actuating the movable element, a movable inertia body normally disconnected from the motor means, an operator operated member for controlling the actuation of the motor means, means for returning said member when released to its initial position, a clutch device for connecting and disconnecting the inertia body and the motor means, and shifting means for the clutch device controlled by the operator operated member.

25 5. In a pressing machine, cooperating pressing elements, one of which is movable toward and from the other, motor means for actuating the movable element, a movable inertia body normally disconnected from the motor means, an operator operated member for controlling the actuation of the motor means, means for returning said member when released to its initial position, a clutch device for connecting and disconnecting the inertia body and the motor means, and shifting means for the clutch device controlled by the operator operated member, said clutch device being normally in its unclutched position and shiftable into clutched position by the operation of the operator operated member.

40 6. In a pressing machine, cooperating pressing elements, one of which is movable toward and from the other, motor means for actuating the movable element, a movable inertia body normally disconnected from the motor means, an operator operated member for controlling the actuation of the motor means, means for returning said member when released to its initial position, a clutch device for connecting and disconnecting the inertia body and the motor means, shifting means for the clutch device controlled by the operator operated member, said clutch device being normally in its unclutched position and shiftable into clutched position by the operation of the operator operated member, and means controlled by the movement of the motor means to hold the operator operated member in its operated position.

65 7. In a pressing machine, cooperating pressing elements, one of which is movable toward and from the other, actuating means for the movable element, a fly wheel normally disconnected from the actuating means, operator operated means for controlling the operation of the actuating means, and means controlled by the operator operated means for connecting and disconnecting the fly wheel with the actuating means.

8. In a pressing machine, cooperating pressing elements, one of which is movable toward and from the other, actuating means for the movable element, a fly wheel normally disconnected from the actuating means, operator operated means for controlling the operation of the actuating means, means to return the operator operated means to its initial position when released by the operator, means for holding the operator operated means

in its operated position when the movable element has closed a predetermined distance, clutch means for connecting and disconnecting the fly wheel with the actuating means, and means controlled by the said operator operated means for operating the clutch device.

9. In a pressing machine, cooperating pressing elements, one of which is movable toward and from the other, motor means for actuating the movable element including a cylinder, a piston movable in the cylinder, motion transmitting means between the piston and the movable pressing element, an operator operated valve for controlling the flow of motive fluid to and from the cylinder, means for returning the valve to its normal position assumed when the press is open, a fly wheel, connections between the fly wheel and one of the parts operated by the piston including a normally open clutch device, means controlled by said valve when operated to shift the clutch device into clutched position, and means to release the clutch device when the valve returns to its initial position.

10. In a pressing machine, cooperating pressing elements, one of which is movable toward and from the other, motor means for actuating the movable element including a cylinder, a piston movable in the cylinder, motion transmitting means between the piston and the movable pressing element, an operator operated valve for controlling the flow of motive fluid to and from the cylinder, means for returning the valve to its normal position assumed when the press is open, a fly wheel, connections between the fly wheel and one of the parts operated by the piston including a normally open clutch device, means controlled by said valve when operated to shift the clutch device into clutched position, means to release the clutch device when the valve returns to its initial position, and means for holding the valve in its open position after the piston has traveled a predetermined distance on its power stroke.

11. In a pressing machine, cooperating pressing elements, one of which is movable toward and from the other, motor means for actuating the movable element including a cylinder, a piston movable in the cylinder, motion transmitting means between the piston and the movable pressing element, an operator operated valve for controlling the flow of motive fluid to and from the cylinder, means for returning the valve to its normal position assumed when the press is open, one of the motion transmitting parts being provided with a rack, a shaft extending crosswise of the rack, a clutch head at one end of said shaft, a pinion mounted on the shaft and meshing with the rack, the shaft being slidable axially of the pinion, a fly wheel mounted concentric with the shaft and having a clutch face complementary to said clutch head, a spring normally holding the clutch head out of clutched position, and a pressure operated motor controlled by said valve for shifting the shaft and thus, shifting the clutch head into engaged position against the action of the clutch spring.

12. In a pressing machine, cooperating pressing elements, one of which is movable toward and from the other, motor means for operating the movable element, motion transmitting parts between the motor means and the movable pressing element including a toggle, an operator operated control member for the motor means, means for returning the control member to its normal position assumed when the press is open,

an inertia body connected to said motion transmitting parts for storing energy, and means for disconnecting the inertia body from said motion transmitting parts when the control member is released and allowed to return to normal position.

13. A pressing machine comprising coacting jaws, a fluid pressure motor including a cylinder and piston having a connecting rod operatively connected to one of the jaws, fly-wheel means carried on a shaft journaled in a bearing on the cylinder, and means operatively connecting the fly-wheel means with the connecting rod.

14. A pressing machine comprising coacting jaws, a cylinder, a piston within the cylinder, a shaft journaled in a bearing on the cylinder and operatively connected with the piston, a fly-wheel rotatably mounted adjacent to one end of the shaft, a clutch to connect the fly-wheel with the shaft, a diaphragm, operating means between the clutch and diaphragm to control the clutch by means of the diaphragm, a fluid connection connecting the diaphragm and the cylinder with a source of fluid pressure, and a control valve in the fluid connection to simultaneously admit pressure to the cylinder and diaphragm to operate the piston to close the press and to operate the diaphragm to engage the clutch.

15. A pressing machine comprising coacting press jaws, a cylinder, a piston having a connecting rod operatively connected with one of the jaws, a gear rack on the connecting rod, and a fly wheel and pinion rotatably mounted upon the

cylinder and having the pinion engaging the gear rack.

16. A pressing machine comprising coacting press jaws, a cylinder having a head on one end thereof with a bearing formed transversely of the cylinder in said cylinder head, a shaft journaled in the bearing, a fly wheel carried on the shaft, a piston and rod reciprocable in the cylinder transversely to the shaft, a gear rack formed on the rod, a pinion fixed on the shaft and engaging the gear rack, and operating connectings between the piston rod and a press jaw.

17. A garment or ironing press comprising coacting pressing jaws, a cylinder, a piston within the cylinder, a shaft journalled in a bearing on the cylinder and operatively connected with the piston, the shaft having axial movement in the bearing, a fly-wheel rotatably mounted upon the cylinder, a clutch to operatively connect the fly-wheel with the shaft and having one clutch member carried upon the shaft, a diaphragm adjacent the end of the shaft, operating means between the diaphragm and the end of the shaft to shift the shaft axially and control the clutch thereby, a fluid connection connecting the diaphragm and the cylinder with a source of fluid pressure, and a control valve in the fluid connection to simultaneously admit pressure to the cylinder to operate the piston and close the press and to operate the diaphragm to engage the clutch.
